UNITED STATES PATENT OFFICE.

WINFIELD S. SMITH, OF PAWTUCKET, RHODE ISLAND, ASSIGNOR OF ONE-HALF TO PHILIP STANLEY SMITH, OF PHILADELPHIA, PENNSYLVANIA.

MACHINE FOR SHAPING BOXES.

SPECIFICATION forming part of Letters Patent No. 700,843, dated May 27, 1902.

Application filed November 27, 1901. Serial No. 83,890. (No model.)

To all whom it may concern:

Be it known that I, WINFIELD S. SMITH, a citizen of the United States, residing at Pawtucket, in the county of Providence and State 5 of Rhode Island, have invented new and useful Improvements in Machines for Shaping Boxes, of which the following is a specification.

This invention relates to box-shaping machines, and especially to machines for imparting a true rectangular shape to boxes made of paper or pasteboard.

In the manufacture of paper boxes it is found to be a most difficult matter to impart 10 a true rectangular shape to the boxes after the blanks have been bent up into shape and the corners of the box stayed owing to the natural tendency of the sides and ends of the box to spring or bulge outward, and this is 15 especially true of paper boxes that are lined or covered owing to the fact that the moisture contained in the paste employed in attaching the lining or covering paper to the box destroys or impairs the rigidity or stiffness of 20 the walls of the box, the result being that said walls spring or bulge outward between the 25 corners of the box, as before explained.

It is the purpose of the present invention to provide a novel, simple, and efficient machine by means of which a true rectangular shape is imparted to the box in such manner 30 that when the box is finished it will retain such shape and will not thereafter be liable to lose it.

To these ends my invention consists in the features and in the construction, combination, and arrangements of parts hereinafter described, and particularly pointed out in the claims following the description, reference 35 being had to the accompanying drawings, forming a part of this specification, wherein—

Figure 1 is a top plan view of my improved machine. Fig. 2 is a vertical sectional view taken on the line 2 2 of Fig. 1. Fig. 3 is a 40 similar view taken on the line 3 3 of Fig. 1. Fig. 4 is a view similar to Fig. 3 of the complete machine, showing a completely finished and shaped box in the act of being ejected from the machine. Fig. 5 is a bottom plan view. Fig. 6 is a detail diagrammatic view 45 illustrating the action of the presser-blocks.

Fig. 7 is a detail sectional view illustrating a modified construction of presser-block, and Fig. 8 is a sectional view taken on the line 8 8 of Fig. 7.

Referring to the drawings, the numeral 1 indicates a flat horizontal table of any suitable or preferred construction supported on legs or uprights 2. Formed in the upper side of the table 1 are four pairs of grooves or 50 guideways 3, said grooves being preferably dovetailed in cross-section and the grooves of each pair being formed parallel with each other, the four pairs of grooves being disposed at right angles to one another and extending from the edge of the table 1 to a central rectangular aperture 4 formed therein. In one pair of the grooves 3 are movably arranged two blocks 5, dovetailed in cross-section and adjustably fitted in said grooves. 55

Fixed transversely to the blocks 5 is a cross-bar 7, preferably of metal, in the inner vertical face of which is formed a longitudinal dovetailed groove 8. Adapted to be detachably secured to said cross-bar is a presser-block 9, preferably of wood, said block at its inner or free edge being convex or formed on the arc of a circle, as indicated at 10 and as most clearly shown in Fig. 1 of the drawings.

To the inner edge of the presser-block 9 is attached by screws or by other suitable means a metallic strip 11, dovetailed in cross-section to fit the dovetailed groove 8 in the cross-bar 7 in which said strip is fitted and held and in which it is adapted to be freely inserted and 65 removed endwise, whereby the presser-block may be freely inserted in and detached from the cross-bar. The presser-block 9 is held in its adjusted position by a bolt and nut 6, that passes through the cross-bar 7 and through a 70 slot 6^a in the table 1. In the arrangement just described the presser-block 9 is designed to be adjusted to a fixed position suitable for shaping boxes of a given size and is intended to remain in such adjusted position as long 75 as boxes of such size are to be shaped on the machine, and I shall hereinafter therefore, for the purpose of differentiating between said presser-block and the other presser-blocks employed in the machine, refer to the 80 presser-block 9 as a "fixed" presser-block,

notwithstanding the fact that it is adjustable 85

toward and from the center of the table in the manner before described. In each of the three other pairs of grooves or guideways 3 are arranged dovetailed blocks or guides 12, similar in all respects to the blocks or guides 5, before described, excepting that they are preferably longer, and rigidly secured to each pair of such blocks or guides 12 is a transverse cross-bar 13, to which are detachably secured presser-blocks 14 in precisely the same manner in which the presser-blocks 10 are attached to the cross-bars 7, the construction of the presser-blocks 9 and 14 being identical. Each of the presser-blocks referred to is under 15 cut or recessed on its inner convex or curved edge, as indicated at 15 and as most clearly shown in Figs. 2, 3, and 4 of the drawings, for the purpose hereinafter explained. To the rear ends of each pair of blocks or guides 20 12 is rigidly secured a strut 16, to the center of which is clamped a hook 17, and engaging said hook is one end of a chain, cord, or flexible connection 18, which leads over a guide-pulley 19, journaled in the table 1 adjacent 25 to the central aperture 4, and from thence leads to a point centrally under said aperture 4, where the three chains or flexible connections 18 are united and connected to one end of a single chain or link 20. In order to permit 30 the chains or flexible connections 18 to pass freely beneath the presser-blocks 14 and cross-bars 13, said presser-blocks and cross-bars are grooved on their under sides, as at 21, through which grooves the chains are 35 adapted to freely travel. To the outer end of each cross-bar 13 is attached one end of a coiled spring 22, the other end of which is fixed to the table 1, said springs operating to normally hold the presser-blocks 14 retracted 40 or withdrawn from the central aperture 4. Journaled at one end on a fixed shaft 23, supported by the legs of the machine, is a treadle 24, provided at its free end with a foot-pedal 25, and attached to said treadle 45 intermediate the ends of the latter is the lower end of the chain or flexible connection 20.

Adapted to normally close the aperture 4 is a hinged box-support 26, consisting of a flat 50 platform, hinged at one side, as at 27, to one of the side walls of the aperture 4 and adapted when raised to close said aperture and lie flush with the upper surface of the table 1. Attached to the under side of the platform or 55 box-support 26 is a cam or a depending foot 28, having a curved or inclined face 29 for the purpose hereinafter explained. Attached to the strut 16 of one of the sliding carriages carrying the presser-blocks 14 is a depending 60 stud-bolt 30, which is adapted to reciprocate in a slot 31, formed in the table 1, (see Fig. 5,) and swiveled intermediate its ends on said stud-bolt is an oscillating latch 32, provided at one end with a hook-shaped extremity 33. 65 Fastened to the under side of the table 1 is a U-shaped strap or guide 36^a, in which is slid-

ably arranged a pusher-bar 34, the extremity of which is bent downward in position to engage the cam 28, pendent from the box-support 26. Said pusher-bar is provided at its 70 outer end with a hook-shaped extremity 35, and attached to said bar is one end of a coiled spring 36^b, the other end of which is attached to the table 1 and operates to move the pusher-bar in a direction to engage the cam 28 and 75 raise the box-support 26 to a horizontal position flush with the table. Fixed to the under side of the table 1 in the path of movement of the latch 32 is a cam 37, consisting of a plate slotted, as at 37^a, and adjustably secured to the table by a bolt 38, said plate having an inclined face 39 with which the end of the latch 32 is adapted to engage, and whereby the latter is oscillated about its fulcrum when the presser-blocks are retracted. 85

The operation of my box-shaping machine is as follows: The box after having been bent into shape and stayed is placed upon the support 26. The operator then depresses the treadle and through the medium of the chains 20 90 and 18 draws the presser-blocks toward each other, thereby thrusting the presser-blocks against the sides of the box and bending or forcing the latter inward beyond the planes of the corners of the box, as illustrated in Fig. 6 of 95 the drawings. After this result has been accomplished the operator removes his foot from the treadle, whereupon the springs 22 immediately operate to retract the presser-blocks. As the blocks are retracted the latch 32 is 100 also retracted and draws back with it the pusher-bar 34 away from and from under the cam 28, whereupon the box-support will immediately drop by gravity and discharge the box. As the presser-blocks approach the end 105 of their outward movement the end of the latch 32 engages the inclined face 39 of the cam 37 and is oscillated about its pivot, so as to disengage and release the pusher-bar 34, whereupon the spring 36 thrusts the pusher-bar forward and causes it to engage the cam 28 and raise the box-support 26 to a position flush with the table 1 in position to receive another box. When the presser-blocks are again moved forward to shape a box, the 115 hooked end 33 of the latch 32 snaps or slips over the hooked end of the pusher-bar 34 in readiness to again retract the latter and drop the box-support when the pressure is removed from the box. When pressure is imparted to 120 the sides and ends of the box in the manner and by the means described, the sides and ends of the box are pressed inward beyond the position they are designed to normally assume in the finished box, and when the pressure is removed from the box said sides and ends assume a perfectly rectangular shape 125 and are prevented from bulging or bowing outward.

I have shown one of the presser-blocks as 130 fixed or stationary; but I wish it to be understood that I do not confine myself to such an

arrangement, it being obvious that all or only a portion of the presser-blocks may be made movable.

Instead of constructing the presser-blocks in one solid piece in the manner before described I may construct each block of three separate pieces or sections, as shown in Figs. 7 and 8 of the drawings, Fig. 7 being a horizontal sectional view of one of the three-part blocks complete. In such arrangement each presser-block consists of three separate sections 40, 41, and 42, each of which has a convex outer or pressing face, and its opposite face is provided with a dovetailed strip 43, that is adjustably fitted in a correspondingly-shaped groove 44 in the carriage 45. Formed in each of the sections 40, 41, and 42 is a bushing 46, through which passes a right and left threaded adjusting-screw 47. The bushing in the central section 41 is unthreaded, while the bushings in the sections 40 and 42 are threaded internally to engage the right and left threads on the adjusting-screw, and the latter is held against longitudinal movement in said central bushing, while free to rotate therein, by a screw 48, that is screwed into said bushing and engages at its end a circumferential groove 49, formed in the adjusting-screw. It will be manifest that by turning the adjusting-screw in one direction or the other the outer sections 40 and 42 of the presser-block will be adjusted toward or from the central section 41 to accommodate the presser-blocks to boxes of different sizes.

Having described my invention, what I claim is—

1. In a machine for shaping boxes, the combination with a support for the box, of means for pressing opposite sides of the box inward beyond the position they are designed to normally assume in the finished box, substantially as described.

2. In a machine for shaping boxes, the combination with a support for the box, of means for pressing the sides and ends of the box inward beyond the position they are designed to normally assume in the finished box, substantially as described.

3. In a machine for shaping boxes, the combination with a support for the box, of means for simultaneously pressing opposite sides of the box inward beyond the position they are designed to normally assume in the finished box, substantially as described.

4. In a machine for shaping boxes, the combination with a support for the box, of means for pressing opposite sides of the box inward beyond the position they are designed to normally assume in the finished box, said means being constructed to apply the pressure first at a point central of said sides and gradually approaching the ends thereof, substantially as described.

5. In a machine for shaping boxes, the combination with a support for the box, of means for pressing opposite sides of the box inward beyond the position they are designed to nor-

mally assume in the finished box, said means being constructed to apply the pressure first at a point central of said sides and gradually 70 approaching the ends thereof, substantially as described.

6. In a machine for shaping boxes, the combination with a support for the box, of means 75 for pressing opposite sides of the box inward beyond the position they are designed to normally assume in the finished box, said means being constructed to apply the pressure to the upper edges of said sides, substantially as described.

7. In a machine for shaping boxes, the combination with a support for the box, of presser-blocks arranged to move toward and from the box-support, means for moving said presser-blocks toward the box-support with a positive pressure, and means for automatically retracting the presser-blocks, substantially as described.

8. In a machine for shaping boxes, the combination with a movable support for the box, of presser-blocks arranged to move toward and from the box-support, means for moving the presser-blocks toward the box-support, means for automatically retracting the 95 presser-blocks, and means constructed to drop the box from between the presser-blocks when the latter are retracted, substantially as described.

9. In a machine for shaping boxes, the combination with a movable support for the box, of presser-blocks arranged to move toward and from the box-support, means for moving the presser-blocks toward the box-support, means for automatically moving the presser-blocks 105 away from the box-support, and means actuated by the retractile movement of the presser-blocks for releasing the box-support to permit it to move from between the presser-blocks, substantially as described.

10. In a machine for shaping boxes, the combination with a rising-and-falling support for the box, of presser-blocks, means for moving the presser-blocks toward the box-support, means for automatically moving the presser-blocks 115 away from the box-support, means actuated by the retractile movement of the presser-blocks for releasing the box-support to permit it to drop and discharge the box, and means for automatically restoring the 120 box-support to its normal position, substantially as described.

11. In a machine for shaping boxes, the combination with a support for the box, of presser-blocks arranged to move toward and from the box-support, said presser-blocks having convex operative faces, means for moving said presser-blocks toward the box-support and means for automatically retracting the presser-blocks, substantially as described.

12. In a machine for shaping boxes, the combination with a support for the box, of presser-blocks arranged to move toward and from the box-support, said presser-blocks having con-

ved undercut operative faces, means for moving said presser-blocks toward the box-support and means for automatically retracting the presser-blocks, substantially as described.

5 13. In a machine for shaping boxes, the combination with a support for the box, of a stationary presser-block arranged on one side of the box-support, a movable presser-block arranged on the opposite side of the box-support, means for moving the movable presser-block toward the box-support and means for automatically retracting the movable presser-block, substantially as described.

10 14. In a machine for shaping boxes, the combination with a support for the box, of a stationary presser-block adjustably arranged on one side of the box-support, a movable presser-block arranged on the opposite side of the box-support, means for moving the movable presser-block toward the box-support and means for automatically retracting the movable presser-block, substantially as described.

15 15. In a machine for shaping boxes, the combination with a support for the box, of a stationary presser-block detachably fixed on one side of the box-support, a movable presser-block detachably arranged on the opposite side of the box-support, means for moving the movable presser-block toward the box-support, and means for automatically retracting the movable presser-block, substantially as described.

20 16. In a machine for shaping boxes, the combination with a support for the box, of a stationary presser-block arranged on one side of the box-support, movable presser-blocks arranged on the remaining sides of the box-support, means for moving the movable presser-blocks toward the box-support, and means for automatically retracting the movable presser-blocks, substantially as described.

25 17. In a machine for shaping boxes, the combination with an apertured table, of a box-support arranged in said aperture, presser-blocks slidably arranged on the table so as to be moved toward and from the box-support, means for moving the presser-blocks toward the box-support to press the box, means for automatically retracting the presser-blocks, and mechanism actuated during the retractile movement of the presser-blocks for releasing the box-support to permit it to drop and discharge the box, substantially as described.

30 18. In a machine for shaping boxes, the combination with an apertured table, of a box-support hinged at one side in said aperture, presser-blocks slidably arranged on the table so as to be moved toward and from the box-support, means for moving the presser-blocks toward the box-support, means for automatically retracting the presser-blocks, and mechanism actuated by the retractile movement of the presser-blocks for releasing the box-support whereby the latter may swing downward and discharge the box, substantially as described.

35 19. In a machine for shaping boxes, the com-

bination with an apertured table, of a box-support hinged at one side in said aperture, presser-blocks slidably arranged on the table 70 so as to be moved toward and from the box-support, means for moving the presser-blocks toward the box-supports, means for automatically retracting the presser-blocks, means actuated by the retractile movement of the 75 presser-blocks for releasing the box-support to permit it to swing downward to discharge the box, and means for automatically restoring the box-support to normal position, substantially as described. 80

20 20. In a machine for shaping boxes, the combination with an apertured table, of a box-support hinged at one side in said aperture and provided on its under side with a pendent cam, presser-blocks slidably arranged on 85 the table so as to be moved toward and from the box-support, means for moving the presser-blocks toward the box-support, means for retracting the presser-blocks, a pusher-bar arranged to engage the pendent cam to raise the 90 box-support, a spring for moving the pusher-bar in the proper direction to raise the box-support, and mechanism actuated by the retractile movement of the presser-blocks for withdrawing the pusher-bar to permit the 95 box-support to swing downward, substantially as described.

21. In a machine for shaping boxes, the combination with an apertured table, of a box-support hinged at one side in said aperture 100 and provided on its under side with a pendent cam, presser-blocks slidably arranged on the table so as to be moved toward and from the box-support, means for moving the presser-blocks toward the box-support, means for retracting the presser-blocks, a pusher-bar arranged to reciprocate in a suitable support 105 and adapted to engage at one end the pendent cam, a hook on the opposite end of the pusher-bar, an oscillatory latch movable with one of 110 the presser-blocks and arranged to engage and withdraw the pusher-bar to drop the box-support when the presser-blocks are retracted, a spring for moving the pusher-bar in a direction to raise the box-support, and a cam arranged in the path of the latch and operating 115 to oscillate the latter and release the pusher-bar, substantially as described.

22. In a machine for shaping boxes, the combination with an apertured table, of a box-support hinged at one side in said aperture 120 and provided on its under side with a pendent cam, presser-blocks slidably arranged on the table so as to be moved toward and from the box-support, means for retracting the presser-blocks, a pusher-bar arranged to reciprocate in a suitable support and adapted to engage at one end the pendent cam, a hook on the opposite end of the pusher-bar, an oscillatory latch movable with one of the presser-blocks 125 and provided at one end with a hook adapted to engage the hook on the pusher-bar and withdraw the latter to drop the box-support, a spring for throwing said latch into engage- 130

- ment with the pusher-bar, an adjustable cam arranged in the path of the latch and operating to cause the latter to release the pusher-bar, and a spring for moving the pusher-bar 5 in a direction to raise the box-support, substantially as described.
23. In a machine for shaping boxes, the combination with a table provided with a box-support, of sliding carriages movably arranged in 10 ways on the table so as to be moved toward and from the box-support, and carrying presser-blocks, a treadle, flexible connections between the treadle and said carriages and operating when the treadle is depressed to move the carriages and presser-blocks toward the box-support, and springs for retracting the carriages and presser-blocks, substantially as described.
24. In a machine for shaping boxes, the combination with a table provided with a box-support, of sliding carriages movably arranged in 15 ways in the table so as to be moved toward and from the box-support, presser-blocks removably carried by said carriages, a treadle, flexible connections leading from the treadle to the carriages, guide-pulleys over which the flexible connections pass, said treadle operating when depressed to move the carriages and presser-blocks toward the box-support, 20 and springs for retracting the carriages and presser-blocks, substantially as described.
25. In a machine for shaping boxes, the combination with a table provided with a box-support and having grooved ways extending at 25 right angles to the box-support, blocks movably arranged in said ways and carrying cross-bars, each of said cross-bars being provided on its inner face with a longitudinal dovetailed groove, presser-blocks each having attached to its outer edge a dovetailed strip, said 30 strips being removably fitted in said grooves, a treadle and intermediate connections for moving the presser-blocks toward the box-support, and springs arranged to move the presser-blocks away from the box-support, 35 substantially as described.
26. In a machine for shaping boxes, the combination with a support for the box, of carriages arranged to move toward and from the 40 support, a presser device carried by each carriage, each presser device comprising separate blocks adjustable toward and from each other, and means for moving said presser devices toward the box-support with a positive pressure.
27. In a machine for shaping boxes, the combination with a support for the box, of presser devices arranged to move toward and from the support, each presser device comprising 45 separate blocks adjustable toward and from each other, and means for moving said presser devices toward the box-support with a positive pressure.
28. In a machine of the class described, a 50 presser-block formed of independently-adjustable sections, each section having a pressing-face constructed to press the side of a box inward beyond the position said side is designed to assume in the finished box.
29. In a machine of the class described, a 55 presser-block formed of independently-adjustable sections, each section having a pressing-face constructed to press the side of a box inward beyond the position said side is designed to assume in the finished box, and 60 means for adjusting said sections toward and from each other.
30. In a machine of the class described, a 65 presser-block comprising a fixed central section, and adjustable end sections.
31. In a machine of the class described, a 70 presser-block comprising a fixed central section and adjustable end sections, and means for moving the end sections toward and from the central section.
32. In a machine of the class described, a 75 presser-block having an outwardly-curved pressing-face adapted to press the side of a box inward beyond the position it is designed to assume in the finished box.
33. In a machine of the class described, a 80 presser-block having a convex pressing-face adapted to press the side of a box inward beyond the position it is designed to assume in the finished box.
34. In a machine of the class described, a 85 presser-block having a curved or convex edge the under side of which is undercut or recessed.
35. In a machine for shaping boxes, means 90 arranged to act upon the sides of the box and bend said sides inward beyond the position they are designed to assume in the finished box.
36. In a machine for shaping paper boxes, 95 means arranged to act upon the sides of the box and bend said sides inward beyond the position they are designed to assume in the finished box, and means for actuating said bending means.
37. In a machine for shaping boxes, means 100 for simultaneously bending opposite sides of the box inward beyond the position they are designed to assume in the finished box.
38. In a machine for shaping boxes, the combination with a support for the box, of means 105 for bending opposite sides of the box inward beyond the position they are designed to assume in the finished box, and means for actuating said bending means.
- In testimony whereof I have hereunto set my hand in presence of two subscribing witnesses.
